(57) **CLAIM**

The ornamental design for a stand for photo storage, as shown and described.

DESCRIPTION

FIG. 1 is a perspective view of a photo storage showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

A portion of FIG. 3 that is shown as a broken line is for illustrative purpose only and forms no part of the claimed design.

1 Claim, 7 Drawing Sheets

FIG. 1

FIG. 2

FIG. 3

FIG. 4

FIG.5

FIG. 6

FIG. 7
